CLAIM

The ornamental design for a license plate, as shown and described.

DESCRIPTION

FIG. 1 is a front elevational view of a license plate showing my design;

FIG. 2 is a rear elevational view thereof;

FIG. 3 is a top plan view thereof;

FIG. 4 is a bottom plan view thereof; and,

FIG. 5 is a right side elevational view, the left side elevational view being the mirror image thereof.

1 Claim, 1 Drawing Sheet

FIG. 3FIG. 1*FIG. 5*FIG. 4*FIG. 2
